(57) CLAIM

The ornamental design for a vanity cabinet, as shown and described.

DESCRIPTION

FIG. 1 is a perspective view of a vanity cabinet showing our new design;

FIG. 2 is a perspective view thereof, with a drawer shown in an opened position; and,

FIG. 3 is a top plan view thereof, with both drawers shown in an opened position.

The broken lines shown are for illustrative purposes only and form no part of the claimed design.
